(57) **CLAIM**

The ornamental design for a mobile phone, as shown and described.

DESCRIPTION

FIG. 1 is a front view of a mobile phone showing our new design.

FIG. 2 is a rear view of the mobile phone in FIG. 1.

FIG. 3 is a left side view of the mobile phone in FIG. 1.

FIG. 4 is a right side view of the mobile phone in FIG. 1.

FIG. 5 is a top side view of the mobile phone in FIG. 1.

FIG. 6 is a bottom side view of the mobile phone in FIG. 1.

FIG. 7 is a front, top, and right perspective view of the mobile phone in FIG. 1.

FIG. 8 is a rear, bottom, and right perspective view of the mobile phone in FIG. 1.

FIG. 9 is a front view of the mobile phone in FIG. 1, shown in an open state;

FIG. 10 is a rear view of the mobile phone in FIG. 1, shown in an open state;

FIG. 11 is a left side view of the mobile phone in FIG. 1, shown in an open state;

FIG. 12 is a right side view of the mobile phone in FIG. 1, shown in an open state;

FIG. 13 is a top side view of the mobile phone in FIG. 1, shown in an open state;

FIG. 14 is a bottom side view of the mobile phone in FIG. 1, shown in an open state;

FIG. 15 is a front, top, and right perspective view of the mobile phone in FIG. 1, shown in an open state; and,

FIG. 16 is a rear, bottom, and right perspective view of the mobile phone in FIG. 1, shown in an open state.

The shade lines in FIGS. 1-16 show contour.

The broken lines immediately adjacent the shaded areas represent the bounds of the claimed design while all other broken lines are directed to environment and are for illustrative purposes only; the broken lines form no part of the claimed design.

1 Claim, 12 Drawing Sheets
